UNITED STATES PATENT OFFICE.

FREDERICK PENTZ BERGH, HUGO J. LOEBINGER, AND HENRY CHARLES NEUBERGER,
OF NEW YORK, N. Y., ASSIGNORS, BY MESNE ASSIGNMENTS, TO GENERAL REDUC-
TION COMPANY, OF NEW YORK, N. Y., A CORPORATION OF NEW YORK.

APPARATUS FOR THE EVAPORATION OF FLUIDS.

1,204,121.

Specification of Letters Patent.

Patented Nov. 7, 1916.

Application filed April 14, 1911, Serial No. 621,142. Renewed April 10, 1916. Serial No. 90,284.

To all whom it may concern:

Be it known that we, FREDERICK P. BERGH, HUGO J. LOEBINGER, and HENRY C. NEUBERGER, citizens of the United States, residing at New York, in the county of New York and State of New York, have invented certain new and useful Improvements in Apparatus for the Evaporation of Fluids, of which the following is a specification.

10 Our invention relates to an apparatus for the evaporation of fluids.

The object of the invention is to provide an apparatus particularly designed for effective utilization in carrying out the process 15 claimed in our application for Letters Patent, Serial Number 464,257, filed November 24th, 1908, (Patent No. 997,950 of July 18, 1911.) While, in carrying out the process set forth in said application various 20 forms of apparatus might be employed, a construction embodying some of the general features of the apparatus described but not claimed in that process application in conjunction with the additional features 25 herein set forth has been found to be effective in use and of particular advantage, enabling the steps of creating and maintaining the different strata in the vaporizing chamber to be carried out.

30 Our invention is embodied in preferable form in the apparatus hereinafter described and illustrated in the accompanying drawings.

In these drawings, Figure 1 is a side view 35 in elevation, partly in vertical section of the apparatus; Fig. 2, a side view partly broken away looking from the left of Fig. 1 toward the right; Fig. 3, a top plan view, partly broken away, on a small scale of the 40 apparatus and Fig. 4, a detail of part of the atomizer.

Referring to the drawings, the fluid to be evaporated and containing in solution, suspension or emulsion, a solid, viscid or oily 45 content is placed in a container vessel 1 and fed therefrom by a pipe 2 to suitable atomizing means 3. These atomizing means are mounted on a support 4 which is attached directly against the inside surface 50 of one wall of a tank, vessel, box or room 5, constituting a vaporizing and collecting chamber. This vessel is polygonal in form, the object of such formation being to insure a straight unimpeded sweep of the

sprayed fluid in a layer across the chamber in distinction from gyratory or vortex movement such as might be given to the spray by a chamber with curved walls. Preferably the vessel is rectangular although in some cases it might be desirable 60 to employ some other polygonal figure, as a heptagonal or hexagonal shape.

The atomizing means 3 preferably extend across the entire width of one wall of the chamber for the purpose of spraying 65 the fluid in a layer covering practically the entire cross area, whereby a complete cover of spray for the vaporizing medium below is provided and the creation and maintenance of this spray in the form of distinct 70 stratum more effectually carried out and preserved during the operation.

The atomizing means may be of any well-known form suitable for converting the fluid into a spray. In the form shown, 75 the fluid being led into the branch pipes of the atomizer, emerges from the upper open ends thereof. An air tank 5, communicating with an air compressor 6, forces air through the pipe 7 and out through the 80 horizontally projecting nozzles 8 disposed over the open nozzles of the fluid pipe and thus the fluid as it emerges from the supply pipe is met by blasts of air which project the fluid from the rear wall in a 85 layer of fine spray across the chamber. The force of the air pressure on the atomizing 90 is so regulated as not to drive the spray across the chamber with such velocity as to strike the opposite wall with a rebounding force so as to avoid breaking up the stratum formation of the spray.

Below the atomizer and above the bottom 95 of the chamber in the wall 9 of the chamber, which wall is at an angle to the wall 95 against which the atomizer is mounted and in the case of the preferred rectangular chamber in one of the walls at right angles and adjacent to the atomizer-supporting wall, there is provided a rectangular opening 10 extending substantially the entire width of the wall 9 and serving to admit a body of air or other vaporizing gas. An expansion and heater box or chamber 11, communicates with this opening, extending the entire length thereof. In this box may be mounted a steam heated coil 12 for the purpose of heating the air or other gas passing 100 105

into the main chamber. A blower 13 preferably also extending the entire width of the box 11 supplies the air or other gas through a flat pipe 14, substantially rectangular in cross section and also coincident in width with that of the box. The cross area of the entrance box and of the opening 10 is greater than the cross area of the supply pipe 14, whereby the air is expanded and the velocity of the current is reduced as it enters the vaporizing chamber so that the vaporizing air or other gas will move across the chamber at a comparatively low velocity, thereby merely occupying the space below the atomizer and avoiding such impact with the opposite wall as to cause a rebound and a mixing and vortex action in the chamber. This controlled velocity in conjunction with the angle to the projection of the spray at which the body of gas moves also serves to form and maintain such body of gas in a stratum separate from the layer or stratum of spray. The formation of this vaporizing stratum above the bottom of the chamber also creates a distinct stratum or quiet zone of gaseous matter below it into which the concentrate resulting from the evaporation drops. The entering body of air or other gas rises and meets the layer of spray and serves to effectively evaporate the fluid wholly or partly and the dried or concentrated product falls to the bottom of the chamber. A gate 15 may be provided at the bottom if desired, to enable the concentrate product to be removed.

Near its upper end and on the side of the chamber at which the atomizer is located and above the latter is provided in the wall of the chamber a longitudinal rectangular effluent opening 16 extending substantially the entire width of the wall. This opening has a greater area than the inlet opening 10 and is of sufficient capacity to permit the unimpeded continuous flow of an amount of vapor equal to the amount of vaporizing air introduced plus the amount of air driven through the atomizer. To regulate this coordinate outward rate of flow of the vapor, a sliding regulator door or shutter 17 adapted to increase or lessen the size of the opening 16, may be provided. The regulated capacity of this exit and the movement of the vapor and other effluent toward the exit at an angle both to the direction of projection of the spray and to the direction of the incoming vaporizing gas insures that the effluent will also be maintained in a distinct stratum above the spray and drawn off at such a rate as to avoid commingling with the other bodies or breaking up the stratification.

From the opening 16 leads a pipe 18 of a width coincident with the width of the opening to avoid obstructing the flow and creating back pressure. This pipe is pref-

erably rectangular in cross-section. It leads the effluent to a collecting chamber 19, the walls of which may be made of gauze or other permeable material, if desired, to permit the escape of vapor and to retain the concentrates.

The strata formed in the main vaporizing chamber are indicated by cross lines and shading. From the lines 20-20 to 21-21 is formed and maintained the lowermost stratum into which the concentrate is dropped. From the line 21-21 to 22-22 is the stratum consisting of the vaporizing body of air or other gas. From the line 22-22 to line 23-23 is the atomized fluid stratum and from the line 23-23 to 24-24 is formed and maintained the effluent stratum, the vapor particles of which pass out of the exit opening.

Having thus described our invention, what we claim is:

1. An apparatus for evaporating fluids containing in solution, suspension or emulsion a solid, viscid or oily content consisting of a polygonal vaporizing chamber, atomizing means placed adjacent one wall of the chamber and operable to project spray in a layer from said wall across the chamber, means to admit in a substantially horizontal sheet a vaporizing body of gas to said chamber below the atomizer and exit means for the vapor, substantially as described.

2. An apparatus for the evaporation of fluids consisting of a vaporizing chamber, a source of fluid supply, atomizing means communicating with said source and mounted adjacent the wall of the chamber and having means to project spray across the chamber, means below the atomizing means to admit a body of moving vaporizing gas in a sheet substantially parallel to the spray but at an angle to the projected movement of the spray, and an effluent opening above the atomizer, substantially as described.

3. An apparatus for the evaporation of fluids consisting of a chamber in which the evaporation is conducted, atomizing means in said chamber operable to direct the spray in a layer across the chamber, means of fluid supply communicating with said atomizer, and an elongated gas admitting opening below the atomizer and extending longitudinally at an angle to the length of the atomizer, and an effluent opening above the atomizer, substantially as described.

4. An apparatus for evaporation of fluids, consisting of a chamber in which the evaporation is conducted, an atomizer in said chamber extending across the same and having means to direct the spray in a horizontal layer across the area of the chamber, said chamber having a gas admitting opening below the atomizer and extending at an angle to the atomizer, means to impel a body of gas through said opening at an angle to the

projected movement of the spray and said chamber having an elongated opening above the atomizer and on the same side of the chamber as the atomizer to permit the escape of the effluent, substantially as described.

5. An apparatus for the evaporation of fluids, consisting of a polygonal vessel, a source of fluid supply, an atomizer located 10 within said vessel against one side wall thereof and extending the entire width of said wall, said atomizer having means to project the spray from the wall across the interior of the vessel in a horizontal layer, 15 said vessel having below the level of the atomizer an elongated, rectangular opening in a side of the wall adjacent to and at an angle to the atomizer-supporting wall, said opening extending substantially the entire 20 width of its wall and a rectangular opening above the atomizer and through the side or wall of the chamber on which the atomizer is mounted, said opening extending substantially the entire width of the wall, means to 25 impel a body of gas through said first opening and an exit pipe leading from the upper opening, substantially as described.

6. An apparatus for the evaporation of fluids consisting of means to supply the 30 fluid, a suitable vessel to receive the fluid, an atomizer for spraying the same, said vessel having an opening below the level of said fluid, means to direct a current of gas through said opening at an angle to the projected movement of the spray, a pipe to supply said gas, and a chamber between the pipe and opening having a greater area than that of the pipe, substantially as described.

7. An apparatus for the evaporation of 40 fluids consisting of a vessel to receive the fluid, an atomizer, said vessel having an elongated opening above said atomizer, a regulating device to control the area of said opening, and means to admit a body of 45 vaporizing gas to the vessel, substantially as described.

8. An apparatus for the evaporation of fluids consisting of a vessel, an atomizer mounted therein, said vessel having an elongated opening below the level of the atomizer, a gas admitting pipe having a cross area equal to the cross area of the opening, 50 said vessel having above the atomizer an elongated effluent opening and a pipe of cross area equal to that of the opening and 55 leading from said opening and a vapor-separating chamber to which said pipe leads, substantially as described.

9. An apparatus for the evaporation of fluids consisting of a closed vessel with 60 atomizing means attached to the wall of the chamber above the bottom thereof to leave a collecting space below the atomizers into which the dried or concentrated particles are permitted to fall by gravity and to be collected away from the air current, and means to project a vaporizing body of gas horizontally across said chamber to vaporize the 65 atomized liquid.

10. An apparatus for the evaporation of 70 fluids consisting of a vessel, atomizing means mounted on the wall of the vessel so as to be adapted to project a spray horizontally across the chamber of the vessel and located above the bottom of the vessel a sufficient 75 distance to permit the dried or concentrated particles to separate from the spray and drop to the bottom of said vessel into a collecting space, and means for admitting and projecting a current of air or other gas from 80 the wall of the vessel across the same in a plane parallel to the plane of projection of the spray.

In testimony whereof we have affixed our signatures in presence of two witnesses.
